UNITED STATES PATENT OFFICE.

ERNEST N. JOHNSON, OF WINNIPEG, MANITOBA, CANADA.

SWITCH-RAIL.

1,393,538.

Specification of Letters Patent.

Patented Oct. 11, 1921.

Application filed December 19, 1919. Serial No. 345,990.

To all whom it may concern:

Be it known that I, ERNEST N. JOHNSON, a subject of the King of Great Britain, of the city of Winnipeg, in the Province of Manitoba, Canada, have invented certain new and useful Improvements in Switch-Rails, of which the following is the specification.

The invention relates to improvements in switch rails for railroad purposes and the general object of the invention is to provide a simply constructed, easily operated, positive and easily installed switch rail which can be manipulated to connect intersecting tracks as occasion may demand.

15 A further and important object of the invention is to construct the switch rail and the operating mechanism therefor such that it is positively locked against movement in both its limiting positions and which form 20 the entire function of carrying and directing the car wheel at the point of intersection of the main line, turn out rail and the side rail with which it is directly associated.

A still further and very important object 25 of the invention is to arrange the switch rail and the operating and locking bars in a manner such that the entire action of unlocking the switch rail in one position, moving it to its limiting second position and subsequently locking it in such second position 30 can be accomplished in a single movement in one direction of the controlling rod and by so doing entirely dispense with a multiplicity of operating actions.

35 A further object is to construct the appliance so that it is entirely weather proof and such that all the rails associated therewith are amply supported and ballasted.

With the above more important and other 40 minor objects in view, which will become more apparent as the description proceeds, the invention consists essentially in the arrangement and construction of parts herein-after more particularly described and later 45 pointed out in the appended claims, reference being had to the accompanying drawings in which:

Figure 1 is a plan view of my switch rail as it appears installed.

50 Fig. 2 is an enlarged detailed plan view of the switch rail.

Fig. 3 is a side view of the same.

Fig. 4 is an inverted plan view of the top plate showing the parts attached thereto.

55 Fig. 5 is a horizontal sectional view through the device, the section being taken

in the plane of the underside of the top plate.

Fig. 6 is a view similar to Fig. 5 with the moving parts in a different position. 60

Fig. 7 is a longitudinal vertical sectional view at 7-7' Fig. 5.

Fig. 8 is a vertical cross sectional view at 8-8' Fig. 5.

Fig. 9 is a plan view of the guide plates. 65

In the drawings like characters of reference indicate corresponding parts in the several figures.

1 and 2 represent the usual main line rails, 3 and 4 side rails and 5 the customary turn 70 out rail passing angularly across between the main line rails. All the rails are carried in the ordinary way by ties or sleepers 6.

My switch rail is installed instead of the 75 customary frog which appears in the location where the turn out rail and inner side rail intersect the main line rail 2 and by installing it I not only do away with the frog but also with the usual guard rails which is a 80 considerable saving in cost.

The switch rail is now described in detail. 7 is a centrally positioned base plate and on the ends of it I mount and secure rivet as indicated at 8 and 9 two end plates 10 and 11 85 the end plates 11 being considerably longer than plate 10. These plates form a bed plate not only for the switch rail but also for the adjacent ends of the main line, turn out and inner side rails. The meeting ends of the 90 rails 2 and 3 are permanently riveted as indicated at 12 to a rail plate 13 which is in turn permanently fastened by bolts 14 to the outer end of the plate 11, there being a space maintained between the plates 13 and 11 by 95 inserted spacers 15 placed on the bolts.

The inner ends of the rails 2 and 5 which converge toward my switch are separated by a spacing block 16 fastened to the rails by horizontally disposed bolts 17 passing 100 through the rails and blocks. To the bases of these rails I permanently fasten as by rivets 18 the rail plate 19 which in turn is secured by bolts 20 to the extending end of the plate 10, spacers 21 being inserted between the rail and end plates. 105

Here I wish it to be observed that the inner ends of the rails extend inwardly slightly beyond the rail plates to which they are attached and overhang the ends of a pivoted top plate 22 which is contained within 110 the same horizontal plane containing the rail

plates and which obviously is spaced from the end plates a fixed distance equal to the depth of the spacers 15 and 21. The top plate is pivotally fastened to the end plate 11 by a king bolt 23, suitable spacers 24 and 25 being interposed on the bolt between the top plate and end plate, the top spacer being securely riveted to the underside of the top plate while the under spacer is permanently riveted to the top side of the end plate. The head of the king bolt is countersunk in the top plate so that it lies flush. The king bolt 23 is located a selected distance in from the meeting ends of the rails 2 and 3 and the end of the top plate remote from the king pin is formed in an arc radial to the king pin as is also the inner end of the rail plate 19.

The end of the top plate adjacent the king pin is cut to allow of the free lateral swinging movement of the top plate a limited distance as required by the manipulation of the switch rail. On the top plate I mount a switch rail 26 which passes lengthwise of the plate and is permanently secured thereto by clamping pieces 27 overhanging the base of the switch rail and fastened by bolts 28 to the top plate. In actual practice the arrangement is such that when the top plate is moved to its limiting position in one direction the switch rail forms a through connection in the main rail 2 and such that when it is turned to its limiting position in the opposite direction the switch rail forms a through connection between the turn out rail 5 and the inner side rail 3.

The mechanism for moving the plate will be later disclosed.

In the space between the base plate and the top plate I locate a turn plate 29 which is practically half a disk and which is pivotally secured centrally by a pivot pin 30 to the top plate. The body of the disk is actually in the plane of the end plates and it is fitted with a boss 31 so that a space is reserved between the body of the disk and the top plate. In this latter space and on the disk I mount two similar substantially L-shaped locking bolts 32 and 33 which have the out-turned ends thereof slotted as indicated at 34 and slidably fastened to the disk by pins 35 and 36, the pins being equi-distant from the center pin 30. The free ends of the bolts extend toward the free end of the top plate and ride the inner end of the end plate 10 and are held for parallel movement in and out by facial projections 37 cast on the under side of the top plate and providing guide slots 38 and 39 receiving the bolts. To the end of the base plate adjacent the end plate 11 I secure permanently as by riveting a pair of spaced guide plates 40 and 41 which are contained in the plane of the end plate and provide between them a peculiarly shaped guideway 42 for the recep-

tion of a locking bar 43 lying between the top plate and the base plate. At the opposite sides of the locking bar and directly above the guide plates I secure permanently by rivets 44 to the top plate, push bars 45, 46 and 47, the bars 46 and 47 being parallel to that 45 and being spaced so that the upper part of the locking bar is positively guided between them.

A rocking lever 48 is pivotally connected by a pivot pin 49 to the top plate and has the ends thereof slotted and receiving pivot pins 50 and 51 connecting it respectively to the turn plate and to the locking bar which it will be observed is notched away on the top side and centrally of its length to receive the end of the said lever. In the space between the top plate, end plate 10 and base plate 7 I locate a pair of upper filler plates 52 and 53 and a pair of under filler plates 54 and 55 which are securely riveted to the under plates and which act to prevent foreign material from lodging in the space occupied by the turn plate and other working parts.

The filler plates are constructed to provide a locking opening or slot 56 adapted to receive one or other of the locking bolts, depending on the shifted position of the switch rail. The slot is located centrally between the ends of the rails 3 and 5 and is closed at top and bottom by the overhanging end of the top plate and the inner end of the end plate 10.

In constructing the parts I desire that the facial projections in striking the filler plates form a positive stop in the limiting positions for the top plate, such occurring when the locking bolt is directly alined with the slot. In order to accommodate the full movement of the top plate I have cut away the upper filler plate at 57.

To one end of the locking bar I connect pivotally an operating bar 58 connected to the bell crank 59 in turn connected to an operating rod 60, the rod being under the direct control of the switch stand (not shown) and arranged so that in the manipulation of the rod 60 the locking bar can be shifted in or out as occasion may demand.

I wish now to refer to the guideway 42. (See Fig. 9.) The guide plate 40 has the opposite ends thereof presenting two curved faces 61 and 62 which are actually radial to the king pin 23 and between these two are like faces the edge of the guide plate presents two oppositely inclining faces 63 and 64 which meet at a central point 65. The guide plate 41 presents two converging faces 66 and 67, the face 67 being parallel with the face 63 of the opposing bar while the face 66 is parallel with the face 64 of the bar 40. The distance between the point 65 and the meeting point 68 of the converging faces 66 and 67 is practically the width of

the locking bar, the locking bar actually sliding between these points.

The locking bar is provided with curved end faces 69 and 70 which are cut off a radius equal to the radius of the arcs 61 and 62 and said faces 69 and 70 are designed in the movement of the locking bar to engage with and ride the faces 61 and 62.

In order to better understand the invention I will now describe the manner in which it operates assuming initially the switch rail 26 is in the through main line position, that is to say it is connecting with the through rail 2 and that in such position of the switch rail the parts are in the position as shown in Fig. 5 of the drawings where it will be observed that the locking bar is in its innermost position and the locking bolt 32 is locking the top late against lateral movement. Upon the operator at the switch stand initially pulling the rod 60 in the direction indicated by the arrow Fig. 1 he effects an initial short movement of the locking bar in the direction indicated by the applied arrow Fig. 5 and here it is to be observed that at the start of the movement the curved face 69 is clear of the curved face 61 and that the locking bar is riding guided by the faces 66 and 64. In the first initial movement of the locking bar which is a purely end shifting one the curved faces 69 and 61 are brought together and during the interval of this movement the rocking lever has been turned to the position shown in dotted outline in Fig. 5 and has effected the unlocking of the bolt 32, the bolts being then in the position as shown in dotted outline in Fig. 5. The switch rail is accordingly unlocked by this initial movement. A further pull in the locking bar causes the curved face 69 to engage with and ride the face 61 which produce a turning movement in the locking bar and re-acts through the plates 45, 46 and 47 to effect the turning on the king bolt of the top plate and consequently the switch rail. When the locking bar has climbed, so to speak, the inclined face 61, the movement of the locking bar again becomes a purely end shifting one and there is no further movement effected in the top plate and the locking bolt 33 is then directly aligned with the slot 56 and the other parts have the position shown in full outline in Fig. 6.

In this position of the bars the switch rail is making a through connection between the turn out rail 5 and the side rail 3. At the time the second locking bolt has been brought to locking position the facial projection 37 has engaged with the filler plate, thereby positively limiting the movement in that direction. Once the locking bar has been brought to the position shown in Fig. 6 a further pull in the rod 60 causes a straight end movement in the locking bar

which effects the turning of the lever 48 and the consequent entrance of the locking bolt 33 in the slot 56 with the final result that the switch rail is positively locked against movement.

From the above disclosure it will be apparent that I am able by my construction to effect the initial unlocking of the switch rail, the swinging of the switch rail and the final locking of the switch rail in the turned position all by one continued movement in the same direction of the rod 60 and accordingly am able to control the whole action of the switch rail by one operating lever.

While I have fully described the operation and action of the locking bar when moving in one direction I wish it to be distinctly understood that upon the locking bar being moved in the opposite direction the action is duplicated, the bolt which is locked at the beginning of the movement being first unlocked; then the switch rail turned and finally the other bolt locked to positively fasten the switch rail against side movement. In this reverse action the faces 62 and 70 act in the same manner as the faces 61 and 69 previously described.

I desire now to direct attention to the bar 43 which, owing to the peculiar arrangement, affords in itself a lock for the top plate. In considering this it will be seen that owing to the fact that the plate can only swing on the king bolt as a fixed center the only time that the plate can move is when one or other of the faces 69 and 70 of the bar is engaged with one or other of the faces 61 and 62. In all other positions no movement can occur in the plate as the locking bar is in all other locations confined to a purely end shifting movement which is opposed to a movement in the arc of a circle centered on the king bolt.

Consequently the top plate carrying the switch rail can be entirely controlled by the locking bar without actually requiring the locking bolts, the locking bar initially locking the plate against turning movement, then swinging it to set the switch rail and again locking it after the swinging movement has occurred.

In such an arrangement the projections 37 form a positive stop at the limitations to offset lateral thrust at the free end of the switch rail in its limiting positions.

While I have described this invention and particularly the action of the locking bar for accommodating the unlocking of an element in one position, the moving of an element to another position and the subsequent locking of that element in the latter position and all controlled by the shifting of the locking bar in one operating movement, still I wish it to be distinctly understood that I do not wish to be restricted to the application of the locking bar and associated

parts to switch rail use as it could be utilized in a great many other mechanical contrivances to do the same work in the single movement of a controlling lever.

5. What I claim as my invention is:—

1. The combination with a main line, a turn out and a side rail, of a bed plate permanently secured to and supporting the aforesaid rails, a top plate pivotally secured to the bed plate and movable laterally between predetermined fixed limiting positions, a movable rail inserted at the frog point permanently mounted on the top plate and designed in one of the limiting positions of the bed plate to make a through main line rail connection and in the other of the limiting positions of the top plate to make a through connection between the turn out and side rails, a pair of locking bolts carried by the top plate and adapted alternately to lock the top plate against movement in its extreme positions of travel and reversible means for effecting in one controlling movement the initial unlocking of the locking bolt, the subsequent turning of the plate to its other limiting point of travel and the final locking of the plate by the other of the bolts against movement in such latter position.
2. The combination with a main line, a turn out and a side rail, of a bed plate permanently secured to and supporting the aforesaid rails, a top plate pivotally secured to the bed plate and movable laterally between predetermined fixed limiting positions a movable rail inserted at the frog point permanently mounted on the top plate and designed in one of the limiting positions of the bed plate to make a through main line rail connection and in the other of the limiting positions of the top plate to make a through connection between the turn out and side rails, a turn plate pivotally secured to the top plate, a pair of locking bolts connected to the turn plate and adapted to be alternately extended in the turning of the turn plate and in their extended position to lock the top plate positively against movement and reversible means for effecting in one controlling movement the turning of the turn plate and the swinging of the top plate and by such movements the initial unlocking of one of the bolts, the subsequent turning of the top plate from one extreme position to the other and the final locking of the top plate in the latter position.
3. The combination with a main line, a turn out and a side rail, of a bed plate permanently secured to and supporting the aforesaid rails, a top plate pivotally secured to the bed plate and movable laterally between predetermined fixed limiting positions, a movable rail inserted at the frog point permanently mounted on the top plate and designed in one of the limiting positions

of the bed plate to make a through main line rail connection and in the other of the limiting positions of the top plate to make a through connection between the turn out and side rails, a turn plate pivotally secured to the top plate, a pair of locking bolts connected to the turn plate and adapted to be alternately extended in the turning of the turn plate and in their extended position to lock the top plate positively against movement, a locking bar having a restricted endwise sliding movement in respect to the top plate, engaging means carried by the bed plate and presenting curved faces formed radial to the pivot point of the top plate and engageable with the complementary curved faces provided at the ends of the locking bar, means for shifting the locking bar and an operating connection between the locking bar and the turn plate.

4. The combination with a main line, a turn out and a side rail, of a bed plate permanently secured to and supporting the aforesaid rails, a top plate pivotally secured to the bed plate and movable laterally between predetermined fixed limiting positions, a movable rail inserted at the frog point permanently mounted on the top plate and designed in one of the limiting positions of the bed plate to make a through main line rail connection and in the other of the limiting positions of the top plate to make a through connection between the turn out and side rails, a turn plate pivotally secured to the top plate, a pair of locking bolts connected to the turn plate and adapted to be alternately extended in the turning of the turn plate and in their extended position to lock the top plate positively against movement, spaced transversely extending push bars permanently secured to the underside of the top plate and spaced from the bed plate, guide plates permanently secured to the bed plate in a location immediately beneath the push plates, one of said guide plates having the opposite ends thereof presenting two curved striking faces radial to the point of the top plate, a locking bar interposed between the top plate and the bed plate and slidably received between the push bars for restricted end movement and having the ends thereof presenting two curved faces complementary to those of the guide plate with which they are designed to engage in the end shifting of the bar, an operating connection between the locking bar and the turn plate and means for moving the locking bar endwise a predetermined distance in either direction.

Signed at Winnipeg, this 20 day of November, 1919.
